G. S. LEWIS

AIR PISTOL OR GUN

Filed Feb. 8, 1927

INVENTOR.
George S. Lewis,
BY
Frank A. Cutler,
ATTORNEY.

UNITED STATES PATENT OFFICE.

GEORGE S. LEWIS, OF SPRINGFIELD, MASSACHUSETTS.

AIR PISTOL OR GUN.

Application filed February 8, 1927. Serial No. 166 698.

My invention relates to improvements in air pistols or guns, and consists essentially of a frame having a barrel fixedly attached thereto, a sliding breech block mounted on said frame behind said barrel, actuating means for said block, a plunger in said block, a spring for said plunger, either a fixed or a movable abutment for the rear end of said spring, sear and trigger members, for said plunger, connected with said frame, a single spring for said sear and trigger members, and a seating finger or pusher, for the ammunition, carried by said block adjacent to the front end thereof, together with such other parts and members as may be necessary or desirable in order to render the pistol or gun complete and serviceable in every respect, all as hereinafter set forth.

The primary object of my invention is to produce an air pistol or gun, of the spring-pressed piston type, that is compact, simple, strong and durable, has comparatively few working parts, which parts are so enclosed as to be thoroughly protected, and withal is highly practical and efficient.

This pistol or gun possesses great shooting power, and is capable of very accurate shooting.

Other objects and advantages will appear in the course of the following description.

I attain the objects and secure the advantages of my invention by the means and mechanism illustrated in the accompanying drawings, in which—

Figure 1 is a side elevation of a pistol which embodies a practical form of my invention, showing the movable parts and members disposed as when the pistol is ready to be discharged; Fig. 2, a rear end elevation of said pistol; Fig. 3, a central, longitudinal, vertical section through the pistol with the parts disposed as in the first view; Fig. 4, a cross section through the breech block, taken on lines 4—4, looking in the direction of the associated arrow, in Fig. 3; Fig. 5, a side elevation of the pistol with the breech block in its retracted or open position; Fig. 6, an enlarged front end elevation of a skirted bullet; Fig. 7, a central, longitudinal section through said bullet; Fig. 8, a side elevation, in partial section, of the rear-end portion of a pistol, illustrating a slightly modified form of construction, and, Fig. 9, a rear end elevation of the parts and members shown in Fig. 8.

Similar reference characters designate similar parts throughout the several views.

Although this pistol will shoot ordinary slugs or bullets, better results may be obtained when a so-called skirted bullet is used for ammunition, such as that represented at 1, 60 in Figs. 3, 6, and 7.

This pistol has a frame 2 a portion of which enters into the construction or formation of a handle 3. In opposite sides of the frame 2 are longitudinally-extending grooves 5. The 65 grooves 5 extend from the rear end of the frame 2 forwardly for about three-quarters of the length of said frame. The frame is recessed at 6 to receive a sear 7, a trigger 8, and a spring 9. Mounted on the front-end portion of the frame, and extending beyond the front end thereof, is a barrel 10. The barrel 10 is secured to the frame 2 by means of a transverse pin 11, one-half of which is in said frame and the other half in said barrel, and 70 a bolt 12 passed upwardly through the frame to be tapped into the barrel. At the inner end of the barrel 10 is a conical projection 13.

The sear 7 is pivotally connected at 14 with the sides of the recess 6 in the frame 2, and the trigger 8 is pivotally connected at 15 with said sides. At the rear end of the sear 14 is an upwardly- and rearwardly-extending projection or finger 16. The forward end of the sear 7 rests on the trigger 8. The recess 6 85 opens through the top of the frame 2, and also through the bottom of said frame, and the trigger 8 has the usual tail-piece which extends downwardly into position to be grasped by the finger when the pistol is discharged. 90 There is the usual guard 17 for the aforesaid trigger tail-piece. The bottom of the recess 6, back of the opening for the trigger tail-piece, is concave, as represented at 42 in Fig. 3, and the spring 9 rests on this concave bottom, between the rear-end portion, underneath of the sear 7, and the back edge of the trigger 8. The spring 9 retains the sear in engagement or contact with the trigger, and normally said trigger in what may be termed 95 its forward position and said sear with the finger 16 in elevated position. A spiral spring is here used, although a bow spring would be applicable.

The sear 7 and trigger 8 are so constructed that, when the finger is applied to the trigger 8 and pressed rearwardly, said trigger, in swinging on the pivot 15, elevates the front end of the sear 7 and depresses the rear end thereof, all against the resiliency of the spring 100 9; then, upon the release of said trigger from or by said finger, said spring operates to re-

store the parts to their normal positions, or to tend to do so.

A breech block 18 is mounted to slide on the frame 2, said block having on the bottom oppositely-disposed, inwardly-extending flanges 19, which are received in the grooves 5 and thus hold said block on said frame, but permitting it to slide thereon. In the bottom of the block 18, above the recess 6, is a longitudinal slot 37 to accommodate the sear finger 16.

Secured in the bore of the block 18, by means of a transverse pin 20, is an abutment 21, from which extends inwardly a centering pin 22 for a spring 23, in the construction illustrated in Figs. 1, 2, 3, and 5. The abutment 21 is grooved, as at 24, to permit the air to escape from the block 18, when said block 18 is drawn forward to close the rear end of the barrel 10 and to compress the spring 23.

A plunger 25 is arranged to slide in the bore in the breech block 18, said plunger being provided with packing, as at 26, to prevent the escape of air between said plunger and the sides of said bore. The packing 26 is adjacent to the forward end of the plunger 25, and adjacent to the rear end of said plunger is an annular groove 27. The groove 27 is adapted to receive the sear finger 16. The spring 23 extends into a bore in the plunger 25, and bears at opposite ends against the inner end of said bore and the inner side of the abutment 21, respectively. The pin 22 also extends part way into the bore in the plunger 25.

Tapped into the front end of the bore in the breech block 18 is a hollow plug 28 interiorly tapered to correspond with the taper of the projection 13 at the rear end of the barrel 10, and adapted to receive said projection when said block is moved into closed position. The forward movement of the plunger 25 is limited by the plug 28. The plug 28 is provided with a pusher 29 for the bullet. The pusher 29 extends into the passage through the plug 28, and has a cross-head 30 at the inner end that is received in a transverse slot in the rear end of said plug, said cross-head being driven into said slot, or otherwise rigidly secured in place in the plug. The function of the finger 29 will be more fully explained in connection with the explanation of the complete operation of the pistol.

An actuating lever 31, for the breech block 18, is pivotally connected at 32 with the frame 3 beneath the barrel 10, and a link 33 connects said lever with said block, one end of said link being pivotally connected at 34 with said lever, and the other end of said link being pivotally connected at 35 with said block adjacent to the forward end thereof. The pivot 32 is much nearer one end than the other of the lever 31, and it is to said first-named end that the link 33 is pivoted at 34. The free end of the lever 31 is offset and formed with a laterally extending, curved lip 36 adapted to fit

over and bear on top of the block 18, when said lever is thrown over in the direction to move said block forwardly.

Starting with the parts and members disposed as in Figs. 1 and 3, the complete operation of the pistol is described as follows:

The lever 31 is swung on the pivot 32 upwardly, forwardly, and downwardly, from the position which said lever occupies in Fig. 1 into that which it occupies in Fig. 5, with the result that the breech block 18 is moved by said lever and the link 33 rearwardly on the frame 2 into the position shown in said last-named view. This movement of the block 18 opens the way to the rear end of the barrel 10, and the operator inserts a bullet 1 in the bore in said barrel at that end, it being understood that said bore extends through the projection 13. In moving rearwardly, the block 18 carries with it the plunger 25 far enough for the sear finger 16 to snap into the groove 27 in said plunger. The air in the bore of the block 18 back of the plunger 25 is forced out through the grooves 24 in the abutment 21. Next the lever 31 is swung upwardly, rearwardly, and downwardly, on the pivot 32, until the lip 36 comes to rest on top of the breech block 18. During this movement of the lever 31 the block 18 is actuated forwardly on the frame 2, by said lever and the link 33, until said block bears against the rear end of the barrel 10, with the projection 13 in the plug 28. At this time the pusher 29 encounters the bullet 1 and seats the same or causes the same to be fully seated in the bore in the barrel. As the block 18 moves forwardly the spring 23 is compressed between the inner end of the bore in the plunger 25 and the advancing abutment 21, because said plunger is now held against forward movement by the sear 7. The parts and members are now disposed as clearly shown in Fig. 3, and the pistol is ready to be discharged by pulling the trigger 8. Upon pulling the trigger 8 the sear 7 is withdrawn from engagement with the plunger 25, and the latter is thus released to the spring 23. The spring 23 at once drives the suddenly released plunger 25 forwardly with great force, and said plunger compresses the air in the block 18 between the plunger and the bullet 1, with the result that said bullet is forced through the barrel 10 and out of the same at a high rate of velocity. The thickness of the pusher 29 with its cross-head 30 is so much less than the diameter of the opening 38 through the plug 28 that there is ample space for the passage of the compressed air on both sides of said pusher. The plunger 25 is driven forward by the spring 23 until said plunger strikes the plug 28.

The pivots 32, 34, and 35 are so relatively positioned that, when the lever 31 is thrown over with the lip 36 on the breech block 8, the plane common to the centers of the pivots

34 and 35 is above a plane parallel therewith in which is located the center of the pivot 32, hence said lever is locked in closed position without liability of becoming accidentally displaced.

The breech block 18 may be closed without compressing the spring 23, if the trigger 8 be pulled to release the plunger 25 soon after said block commences to move forward, such 10 action permitting said plunger to be carried forward with said block. This is the preferred condition when the pistol is not in use.

In the modification illustrated in Figs. 8 and 9, a fixed abutment 39 is provided for 15 the spring 23, instead of the movable abutment 21. The abutment 39 is very similar to the abutment 21, except that the former is an integral part of or affixed to the frame 2. There is a longitudinal slot 40 in the bottom 20 of the breech block 18 to accommodate a connecting part 41 between the frame 2 and that part of the abutment 39 which is in the bore of said block. The abutment 39 has therein grooves 24 for the passage of air as in the 25 other example, and said abutment also has a pin (22) attached thereto for the purpose of centering the spring 23.

In the modified construction the spring 23 is compressed on the rearward movement of 30 the breech block 18, instead of on the forward movement thereof, because, when said block is moved rearwardly and with it the plunger 25, the spring 23 is compressed between said plunger and the stationary abutment 39. At 35 the end of the rearward movement of the parts the sear 7 engages the plunger 25, as in the other example, and causes the spring 23 to be held under compression while the block 18 is moved forward to close the rear end 40 of the barrel 10, and until the trigger 8 is actuated to cause said sear to release said plunger. Otherwise the construction and operation of the parts and members are similar in both cases.

The breech block 18 can be opened and closed without leaving the spring 23 under compression, provided the trigger 8 be pulled to prevent the sear 7 from engaging the plunger 25 at the time said block is moved forwardly.

When the breech block is closed, the pusher 29 seats the bullet in the barrel, even if said bullet falls back or down a short distance as may occur in the event the pistol be elevated 55 at the muzzle while said block is closing, and the bullet is too loosely held after being initially inserted by hand.

The plug 28 should have an air-tight fit with the barrel projection 13.

No essential change would be involved in embodying this invention in a gun instead of in a pistol.

More or less change in the shape, size, construction, and arrangement of some or all 65 of the parts of this pistol or gun, in addition

to those hereinbefore specifically pointed out, may be made without departing from the spirit of my invention or exceeding the scope of what is claimed.

What I claim as my invention, and desire to 70 secure by Letters Patent, is—

1. The combination, in an air pistol or gun, with a frame provided with a fixed barrel, and further provided with engaging and releasing means for a plunger, of a 75 breech block slidably mounted on said frame behind and in line with said barrel, and adapted to be moved rearwardly until its rear end is clear of said frame, a plunger arranged to slide in said block, and to be engaged by and released from said engaging and releasing means, an abutment, a spring interposed between said plunger and said abutment, and movable means between said frame and block 80 to actuate the latter forwardly and rearwardly on the former, and thereby to cause said spring to be compressed, and said plunger to be delivered to the control of said engaging and releasing means.

2. The combination, in an air pistol or gun, 85 with a frame provided with a fixed barrel, and further provided with cooperating spring-pressed sear and trigger members, of a breech block slidably mounted on said frame behind said barrel, and slotted for the reception of a portion of said sear, an abutment secured in the rear end of said block, a plunger slidably arranged in said block in front of said abutment, and having a part 90 adapted to be engaged by and released from said sear member, a spring interposed between said plunger and said abutment, and means pivotally connected with said frame and block to move the latter forwardly and rearwardly.

3. In an air pistol or gun, a frame provided 95 with a fixed barrel, and further provided with sear and trigger members, a breech block slidably arranged on said frame behind said barrel, a plunger in said block adapted to be carried thereby into a position to be engaged by said sear member, and adapted to move independently in said block when released from said member, a spring bearing on said plunger from behind, an abutment for the rear end 100 of said spring, a perforated plug in the forward end of said block to limit the forward movement in said plunger, a bullet pusher in the opening in said plug, but of less area transversely than that of said opening to permit air to pass therethrough, and means pivotally connected with said frame and said block 105 for actuating the latter toward and away from said barrel.

4. In an air pistol or gun, a frame provided 115 with a fixed barrel, and further provided with sear and trigger members, a breech block slidably arranged on said frame behind said barrel, a plunger in said block adapted to be carried thereby into a position to be engaged 120

by said sear member, and adapted to move independently in said block when released from said member, a spring bearing on said plunger from behind, an abutment for the rear end of 5 said spring, said abutment being recessed for the escape of air, and means pivotally connected with said frame and said block for actuating the latter toward and away from said barrel.

- 10 5. The combination, in an air pistol or gun, with a frame provided with a fixed barrel, and further provided with cooperating trigger and sear members, of a breech block slid- 15 ingly arranged on said frame back of said barrel, and adapted to be moved from en- gagement with the barrel rearwardly beyond the back end of the frame, and forwardly again into said engagement, a plunger slid- 20 ingly arranged in said block, and having a part to be engaged by and released from said sear member, a spring bearing at one end against said plunger, an abutment for the opposite end of said spring, an exterior lever 25 pivotally connected intermediate of its ends directly with said frame, and an exterior link pivotally connected with one end of said lever and with said block, whereby said block is actuated forwardly when said lever is 30 swung on its pivot upwardly, over, and downwardly into normal position, and rearwardly when said lever is swung on its pivot from normal position upwardly, over, and down- 35 wardly into a position where it extends beyond the muzzle end of the barrel.
- 35 6. The combination, in an air pistol or gun, with a frame provided with a fixed barrel, and further provided with cooperating trigger and sear members, of a breech block slid- 40 ingly arranged on said frame back of said barrel, and adapted to be moved from engage- 45 ment with the barrel rearwardly beyond the back end of the frame, and forwardly again into said engagement, a plunger slid- 50 ingly arranged in said block, and having a part adapted to be engaged by and released from said sear member, a spring bearing at one end against said plunger, an abutment for the opposite end of said spring, an exterior lever 55 pivotally connected intermediate of its ends directly with said frame, and an exterior link pivotally connected with one end of said lever and with said block, whereby said block is actuated forwardly when said lever is 60 swung on its pivot upwardly, over, and

downwardly into normal position, and rear- 55 wardly when said lever is swung on its pivot from normal position upwardly, over, and downwardly into a position where it extends beyond the muzzle of the barrel, said lever having at its free end a lip adapted to be 60 received on said block when said lever is 65 swung into normal position, and the pivots for said lever and link being so related that, when said lip is on said block, the center of the pivot, by means of which the lever is 70 directly connected with the frame, is below the plane common to the centers of the other two pivots, and the lever and connected parts are locked in place.

7. In an air pistol or gun, a frame, a barrel 70 mounted on said frame, and a hollow breech block slidingly mounted on said frame be- 75 hind and in line with said barrel, said block being provided at the front end with a pusher for a bullet inserted in said barrel, which pusher is of less area transversely than that of the bore in said block, and of greater area transversely than the bore in said barrel, at adjacent ends of said bore.

8. The combination, in an air pistol or gun, 80 with a frame provided with a fixed barrel, of a breech block slidingly mounted on said frame behind said barrel, a perforated plug in the forward end of said block, and a pusher carried by said block and extending into the 85 opening therein, said pusher being of less area transversely than that of the opening through said plunger to permit of the passage of air therethrough, and adapted, when ad- 90 vanced with said block, to force into said barrel a bullet inserted in the breech thereof.

9. In an air pistol or gun, a frame, a barrel mounted on said frame, and having at the rear end a conical projection, a breech block mounted to slide on said frame behind said 95 barrel, a slotted plug in the front end of said block, said plug having an opening there- 100 through the sides of which at the forward end are adapted to receive said projection, and a pusher in said opening, said pusher being of less area transversely than that of the opening through said plug to permit of the passage of air therethrough, having a head seated in the slot in said plug, and adapted, 105 when advanced with said plug, to force into said barrel a bullet inserted in the breech thereof.

GEORGE S. LEWIS.
